UNITED STATES PATENT OFFICE.

EDWARD A. LANGTON, OF NEW YORK, N. Y., ASSIGNOR OF ONE-HALF TO CHARLES T. HAYNER, OF NEW YORK, N. Y.

NON-REFILLABLE BOTTLE.

1,134,210.

Specification of Letters Patent.

Patented Apr. 6, 1915.

Application filed April 4, 1914. Serial No. 829,411.

To all whom it may concern:

Be it known that I, EDWARD A. LANGTON, a citizen of the United States, and residing at New York, in the county of New York and State of New York, have invented certain new and useful Improvements in Non-Refillable Bottles, of which the following is a specification, such as will enable those skilled in the art to which it appertains to 10 make and use the same.

This invention relates to bottles, jugs, jars and similar vessels, and the object thereof is to provide a vessel of this class which having been once filled and emptied of its 15 contents cannot be refilled or re-used.

The invention described and claimed here-with is an improvement on that described and claimed in Letters Patent of the United States No. 1,047,662, issued December 17, 20 1912, and said invention is fully disclosed in the following specification of which the accompanying drawing forms a part, in which the separate parts of my improvement are designated by suitable reference 25 characters in each of the views, and in which;—

Figure 1 is a central vertical sectional view of the neck portion of a bottle provided with my improvement;—Fig. 2 a 30 similar view showing the bottle inverted or partially so, and;—Fig. 3 a cross section on the line 3—3 of Fig. 1.

In the drawing forming part of this specification, I have shown at a the neck of a 35 bottle of the usual or any preferred form, and in which is an annular valve seat a^2 forming a passage way a^3 adapted to be closed by a valve b normally seated on said valve seat, and comprising a cylindrical top 40 portion or head having a downwardly directed projection b^2 which extends below said valve seat. I also secure in the neck of the bottle at a predetermined distance above the valve seat a^2 a conical plug c having a 45 cylindrical base portion c^2 and a central longitudinal bore or passage c^3 which is also preferably tapered from the bottom to the top of said plug, and in said bore or passage are longitudinal ribs c^4 any desired number 50 of which may be employed.

In the construction shown, the plug c , or the base thereof, rests on an annular shoulder a^4 in the neck of the bottle, and formed in said neck above said shoulder is an annular groove a^5 which communicates with an

annular groove c^5 in the base portion of the plug c , and in order to secure said plug in the neck of the bottle, the grooves a^5 and c^5 are filled with cement d , but my invention is not limited to this particular method of 60 securing the plug in the neck, and said plug may be secured in position in any desired manner.

I also provide a closure stopper d^2 which is adapted to fit in the top of the neck of the 65 bottle, and which is provided with an annular rim portion d^3 which rests on said neck, and passing vertically through the plug c and secured centrally in the stopper d^2 is a rod e the lower end of which is provided with a head e^2 which, when the parts 70 are assembled into the position shown in Fig. 1, extends to within a very short distance of the valve b , as clearly shown in said figure.

All the parts of the neck attachment involving the valve b , the plug c , the stopper d^2 and the rod e are preferably composed of glass, porcelain or similar material, and the stopper d^2 is provided centrally of the bottom thereof with a recess or chamber d^4 80 adapted to receive the top portion of the plug c , and while the top portion of the plug c is conical in form and the side walls of the recess or chamber d^4 of similar form, 85 this is not an essential element of the construction, and said parts may be cylindrical in form, if desired.

In assembling the parts c and e , the rod e is first passed upwardly through the plug c 90 and secured in the top of the stopper d^2 , after which the plug c is inserted into the neck of the bottle, and the stopper d^2 is raised and the liquid cement for filling the grooves a^5 and c^5 is poured between the neck 95 of the bottle and the stopper d^2 , while the latter is in a raised position.

In the use of a bottle or similar vessel provided with my improvement, the said vessel is first filled with the desired contents, 100 after which the valve b is dropped into position, and the assembled parts c , d^2 and e are then placed in the neck and the plug c secured as above described, and if at any time, it is desired to empty the bottle, or discharge 105 a portion of its contents, the stopper d^2 is raised and the bottle inverted or tilted, as shown in Fig. 2, when the parts c , d^2 and e will assume the position shown in said figure, the valve b will drop forwardly or 110

downwardly and the contents of the bottle will flow out through the plug *c* and into and around the stopper *d*² and out, as indicated by the arrows *X*.

- 5 The head *e*² of the rod *e* is valve-shaped in form, and the ribs *c*⁴ in the bore of the plug *c* are intended to prevent the said head *e*² from closing the plug *c* when the bottle is inverted or tilted, as shown in Fig. 2.
- 10 The valve *b* may also be made so as to serve as a float, and if an attempt be made to force liquids into the bottle, while holding the latter in an upright or partially upright position, said valve will rise to its seat, and
- 15 no liquids can enter the bottle.

It will be observed that the chamber *f*, the valve *b* and the head *e*² of the rod *e* are so proportioned that the valve *b* has but slight movement, and the downwardly directed projection *b*² thereof always holds said valve in position for operation, and the proportional sizes of these parts may be so regulated that the valve *b* will have even slighter movement than with the construction shown.

25 Having fully described my invention,

what I claim as new and desire to secure by Letters Patent is;—

A bottle or other vessel provided with a neck in the bottom of which is an annular valve seat, a valve adapted to be seated on said valve seat and provided with a downwardly directed projection, a hollow plug secured in said neck and having an upwardly directed extension, a stopper adapted to close said neck and provided centrally of the bottom thereof with a recess or chamber adapted to receive the extension of the plug, and a rod passed upwardly through said plug and secured in said stopper and movable longitudinally through said plug and provided at its lower end with a head normally supported adjacent to said valve.

In testimony that I claim the foregoing as my invention I have signed my name in presence of the subscribing witnesses this 2nd day of April 1914.

EDWARD A. LANGTON.
